UNITED STATES PATENT OFFICE.

THOMAS W. CURRY AND JOHN F. GODFREY, OF PICTOU, NOVA SCOTIA, CANADA, AS
SIGNORS OF ONE-FIFTH TO FRANK ADAMSON, ONE-FIFTH TO DONALD F. MORRISON,
AND ONE-FIFTH TO D. HERDMAN CAMERON, ALL OF PICTOU, NOVA SCOTIA, CAN-
ADA.

TURNING GEAR.

Application filed June 26, 1923. Serial No. 647,902.

To all whom it may concern:

Be it known that we, THOMAS W. CURRY and JOHN F. GODFREY, both subjects of the King of Great Britain, residing at Pictou, 5 Province of Nova Scotia, Canada, have invented certain new and useful Improvements in Turning Gears; and we do hereby declare that the following is a full, clear, and exact description of the invention, such as will enable others skilled in the art to which it appertains to make and use the same.

The present invention pertains to novel improvements in a turning gear for use in connection with engines. Although the device may be used in conjunction with engines of any character, it is designed primarily for turning over an engine on board ship by operating directly upon the power shaft.

The principal object of the invention is the provision of a device of this character adapted to work in either direction. To this end, the shaft carries a pair of oppositely cut ratchets with which are associated actuating hand levers and pawls adapted for selective engagement with the ratchets. In a modified construction there is provided a single power lever instead of the two hand levers, this power lever carrying the two pawls which engage the ratchet. The power lever further carries a lever mechanism for bringing one or the other of the pawls into engagement with a ratchet. In an alternative form of the power lever construction, the pawl actuating device is operated by a lever which is not carried by the power lever and is consequently independent thereof. This construction results in safer operation, since the hands of the operator are not in the way of the moving power lever.

It will be apparent that a device constructed in accordance with the invention can be used for moving the engine out of dead center, starting the engine, or moving it slightly when it is under repair.

The invention is fully disclosed in the following description and in the accompanying drawings in which:

Figure 1 is a side elevation of the device applied to a shaft;

Figure 2 is a front elevation;

Figure 3 is a section on the line 3-3 of Figure 2;

Figure 4 is a front elevation of a modification;

Figure 5 is an edge view thereof; 55
Figure 6 is a section on the line 6-6 of Figure 4; and,

Figure 7 is a front elevation of a still further modification.

Reference will now be had to these views 60 by means of like characters which are employed to designate corresponding parts throughout.

The numeral 1 indicates the propeller shaft of a ship or the power shaft of any 65 form of engine. The turning gear comprising the present invention is mounted on a suitable support consisting of a pair of spaced uprights 2 and 3 through which the shaft passes. Adjacent the inner faces of 70 these uprights the shaft carries a pair of ratchet wheels 4 and 5 the teeth of which are cut in opposite directions as is apparent by a comparison of Figures 1 and 3. To the uprights 2 and 3 are pivoted hand levers 6 75 and 7 carrying pivoted latches 8 and 9 at the upper ends and pawls 10 and 11 at the lower ends. The latch 8 is connected to the pawl 10 and the latch 9 to the pawl 11 by means of rods 12 and 13 respectively. The latches 80 are so pivoted to the hand levers as to assume by gravity the position shown in Figure 3 wherein the pawls are free from the ratchets. When it is desired to turn the shaft, as for example to take the engine out of dead 85 center, one of the latches is pressed inwardly towards its lever according to the ratchet to be engaged. The lever is now pulled against the teeth of the ratchet whereby the 90 shaft is turned.

In Figure 4 is shown a modified form for use in places where the engine cannot be turned over by hand power. The shaft 20 carries a pair of oppositely cut ratchets 21 95 and 22 in the same manner as the form illustrated in Figures 1, 2 and 3. Above the ratchets a power lever 23 is pivoted on a spindle 24 which extends substantially parallel with the shaft. Through the lower portion of the power lever is passed a stem 25 to one end of which is secured the vertex of a bell crank lever comprising an operating arm 26 and an actuating arm 27. The remaining end of the stem 25 carries an actuating arm 28 extending oppositely to the member 27. 100

In the lower edge of the power lever 23 are cut a pair of notches 29 and 30 in which 105

are pivoted pawls 31 and 32 adapted for cooperation with the ratchets 21 and 22 respectively. To the free ends of the pawls are pivoted rods 33 and 34 respectively which pass through the arms 27 and 28 respectively. The upper ends of the rods are fitted each with a head 35 against which bears one end of an expansion spring 36, the remaining end bearing against the respective arm 27 or 28. By means of this device the pawls are normally maintained out of engagement with the ratchets.

It will be apparent that either ratchet 21 or 22 may be engaged by its respective pawl by shifting the member 26 in one direction or the other. For turning the shaft, the power lever 23 is then moved on its pivot 24 in the desired direction of rotation. The power lever is to be actuated by an auxiliary engine. The advantage of this device is that it does away with the necessity of the slip eccentric on the auxiliary engine, whereas the slip eccentric may be used on the main engine to good advantage by means of this device. This does away with the Stevenson link now used, and is one of the important improvements which the device will make in the system now in use.

In the form shown in Figure 7, the mechanism for setting the pawls is spaced at a distance from the power lever. In this construction a hand lever 40 is intermediately pivoted as at 41 at a point independent of the power lever. The member 40 is connected to the operating arm 26' of the bell crank lever by means of a link 42. The connections between the ends of the link and the members 26' and 40 are in the nature of universal joints 43 to allow for the swinging of the link when it is moved by the power lever 23 and also for the pivotal movement between this link and the lever arms to which it is connected. After one of the pawls is set by means of the lever 40, the power lever is moved in the manner already pointed out in connection with Figures 4, 5 and 6.

While a specific embodiment of the inven-

tion has been illustrated and described, it is to be understood that various alterations 50 in the details of construction may be made without departing from the spirit of the invention as indicated by the appended claims.

Having thus fully described the invention, what we claim as new and desire to protect by Letters Patent is:—

1. A turning gear comprising in combination with a shaft a pair of oppositely cut ratchets carried thereby, a power lever 60 pivoted on an axis substantially parallel with the shaft, pawls pivoted to the lever and adapted for independent engagement with the ratchets, an actuating lever pivoted to the power lever, arms extending from said actuating lever in opposite directions and engaging said pawls.

2. A turning gear comprising in combination with a shaft a pair of oppositely cut ratchets carried thereby, a power lever 70 pivoted on an axis substantially parallel with the shaft, pawls pivoted to the lever and adapted for independent engagement with the ratchets, means associated with the power lever for actuating said pawls, a 75 pivoted hand lever spaced from the power lever and operatively connected to said means.

3. A turning gear comprising in combination with a shaft a pair of oppositely cut 80 ratchets carried thereby, a power lever pivoted on an axis substantially parallel with the shaft, pawls pivoted to the lever and adapted for independent engagement with the ratchets, an operating lever pivoted 85 to the power lever, arms extending from said operating lever in opposite directions and engaging said pawls, a hand lever pivoted in spaced relation from and independent of said power lever and linked to said operating lever.

In witness whereof we have hereunto set our hands.

THOMAS W. CURRY.
JOHN F. GODFREY.
